UNITED STATES PATENT OFFICE.

GEORGE H. ROSE, OF BEN AVON, PENNSYLVANIA, ASSIGNOR TO THE AMERICAN STEEL
AND WIRE COMPANY OF NEW JERSEY, A CORPORATION OF NEW JERSEY.

BLAST FURNACE.

Application filed January 16, 1923. Serial No. 613,003.

To all whom it may concern:

Be it known that I, GEORGE H. ROSE, a citizen of the United States, and resident of Ben Avon, in the county of Allegheny and 5 State of Pennsylvania, have invented certain new and useful Improvements in Blast Furnaces, of which the following is a specification.

This invention relates to blast furnaces, 10 and more particularly to means for supporting the furnace charging bells and bell operating mechanisms.

The principal object of the present invention is to provide means supported on the 15 bleeder pipes of the furnace for supporting the charging bells and bell operating mechanism, thereby eliminating the necessity of building a separate supporting structure above the furnace for these parts.

20 The advantages of the present construction will be readily appreciated by those skilled in the art. For instance, the weight of the structure supported on the top of the furnace is greatly reduced, and the cost 25 of building a separate supporting structure is avoided.

In the drawings, Figure 1 is a side elevation, partly in section, of the upper portion 30 of a blast furnace having my invention applied thereto.

Figure 2 is a side elevation taken at right angles to Figure 1.

Figure 3 is a sectional plan of the furnace on the line III—III of Figure 1.

35 Referring more particularly to the drawings, the numeral 2 designates the upper end of the blast furnace stack provided with the usual opening in which is mounted a fixed hopper 3, which has its lower or bottom 40 opening controlled by a bell 4, while the upper portion is closed by a frusto-conical cap 5 upon which is mounted a receptacle or small, straight sided hopper 6. The lower end of the hopper 6 is controlled by a normally closed bell 7. A chute or hopper 8 is mounted above the hopper 6 and is adapted to receive the material to be charged in the furnace from the skip hoists or other elevating means (not shown).

50 The furnace stack 2 is provided with the usual bleeder pipes 9 and downcomer pipes 10. The bleeder pipes are riveted to the shell 11 of the stack and are reinforced by vertical angle members 12 riveted thereto.

55 The bleeder pipes 9 extend outwardly and

upwardly, and the angle reinforcing members 12 extend vertically below the bend in the bleeder pipes and are supported at their lower ends by brackets 13, which are secured to the stack shell. It will thus be seen that 60 the vertical stresses of the bleeder pipes 9 are partly taken by the members 12 and brackets 13.

In the construction shown, four bleeder pipes 9 are used, which extend upwardly 65 from the furnace at diametrically opposite points so that they define the corners of a rectangle.

The bleeder pipes 9 are tied together so as to prevent outward displacement by four 70 pairs of girders 14, 15, 16 and 17, respectively. The girders 14, 15, 16 and 17 are secured to brackets 14^a, 15^a, 16^a and 17^a, respectively, which are riveted or otherwise secured to the bleeder pipes 9. 75

The girders 16 and 17 extend at right angles to, and have their bottom faces on a line with the top faces of the girders 14 and 15.

The girders 16 and 17 have a widened or 80 dropped portion intermediate their ends forming feet 18 which support the ends of a pair of girders 18^a which extend parallel to the girders 14 and 15.

The bell 7 is suspended from tubular 85 member 19 which has its upper end pivotally connected to one end of a counterweighted operating lever 20 pivoted intermediate its ends on a bracket 21 mounted on the girders 25.

The bell 4 is suspended from a rod 22 which extends upwardly through and above the tubular member 19 and has its upper end pivotally connected to one end of a counterweighted operating lever 23 which is 90 pivoted intermediate its ends on a bracket 24 mounted on girders 18^a.

The girders 25 have their end portions extended downwardly forming feet 25^a, which engage and are secured to the upper faces 100 of the girders 16 and 17.

The counterweighted levers 20 and 23 are provided with operating cables 27 and 28, respectively, which are trained over suitable sheaves 29, which are journaled on the skip bridge 30, the upper part of which is shown in Figure 1, and extend to a suitable prime mover (not shown). The cables 27 and 28 are adapted to positively raise the counterweighted ends of levers 20 and 23 to 105 110

lower the bells 7 and 4, respectively, when charging the furnace.

The upper ends of the bleeder pipes 9 are tied together by beams 31 and truss braces 32. Suitable flooring (not shown) may be supported on the beams 31, if desired to form a platform upon which workmen may stand when inspecting or repairing the relief valves on the top of the bleeder pipes 9.

10 The charging apparatus described in the foregoing specification is of the well known McKee type and its operation is well known to those skilled in the art.

The novelty of the present invention lies 15 in supporting the charging bells and their operating mechanism on the bleeder pipes of a blast furnace, thereby eliminating the necessity of building a separate supporting structure for these parts.

20 I claim:-

1. The combination with a blast furnace having a plurality of bleeder pipes extending upwardly therefrom, a charging hopper and bell, of girder members arranged 25 transversely of and secured to said bleeder pipes, and means for supporting and operating said bell mounted on said girders.

2. The combination with a blast furnace having a plurality of bleeder pipes extending upwardly therefrom, and a charging 30 hopper and bell, of transverse girder mem-

bers arranged between and secured to said bleeder pipes, means for reinforcing said bleeder pipes vertically, and means mounted on said transverse girders for supporting 35 and operating said bell.

3. The combination with a blast furnace having a plurality of bleeder pipes extending upwardly therefrom, and a charging 40 hopper and bell, of transverse girder members arranged between and secured to said bleeder pipes, vertical reinforcing members secured to said bleeder pipes, and means mounted on said transverse girder members for supporting and operating said bell. 45

4. The combination with a blast furnace having a plurality of bleeder pipes extending upwardly therefrom, and a charging hopper and charging bells, of transverse 50 girder members arranged between and secured to said bleeder pipes, vertical reinforcing means secured to said bleeder pipes and said furnace shell, counterweighted supporting and operating levers for said bells, and means mounted on said transverse girders 55 for supporting said levers, whereby said bells and their operating levers are wholly supported through said girders by said bleeder pipes.

In testimony whereof, I have hereunto 60 signed my name.

GEORGE H. ROSE.
